UNITED STATES PATENT OFFICE.

THOMAS BRADLEY, OF TRINIDAD, COLORADO, ASSIGNOR OF ONE-HALF TO WILLIAM CHILDS, OF STARKVILLE, COLORADO.

BURIAL-CASE.

1,401,037.

Specification of Letters Patent. Patented Dec. 20, 1921.

Application filed November 22, 1919. Serial No. 339,847.

To all whom it may concern:

Be it known that I, THOMAS BRADLEY, a citizen of the United States, residing at Trinidad, in the county of Las Animas and

5 State of Colorado, have invented certain new and useful Improvements in Burial-Cases, of which the following is a specification.

This invention relates to burial caskets, and the primary object of the invention is 10 to provide an improved sanitary casket constructed in such a manner as to protect the body against perceptible deterioration for a considerable length of time, and permit the body to be viewed when desired.

15 Another object of the invention is to provide an improved casket embodying an inner transparent structure formed of impervious material having water, air and vermin proof qualities, and an outer protecting casing 20 suitably carved or otherwise ornamented, so as to present a pleasing appearance to the eye.

25 A further object of the invention is to provide a casket having an improved construction which will permit the easy and convenient insertion of a corpse therein, without necessitating the rising or lowering of the corpse in or out of the casket.

30 A still further object of the invention is to provide an improved casket of the above character which is durable and efficient in use, one that is simple and easy to manufacture, and one which can be placed upon the market at a reasonable cost.

35 Other objects of the invention will appear in the following detailed description taken in connection with the accompanying drawings, forming a part of this specification, and in which drawings:

40 Figure 1 is a side elevation of the improved casket showing the same positioned adjacent to the laying out board and the corpse positioned thereon ready for insertion into the casket.

45 Fig. 2 is an enlarged vertical longitudinal section through the improved casket showing the same in its sealed condition with the corpse positioned therein.

50 Fig. 3 is an enlarged detail fragmentary plan view of the casket with the cover swung

open, showing the means carried by the inner casing for exhausting the air therefrom.

Fig. 4 is a transverse section through the improved casket showing the cover in its 55 opened position, and

Fig. 5 is an end elevation of the improved casket.

Referring to the drawings, in detail, wherein similar reference characters designate corresponding parts throughout the several views, the letter A indicates the improved casket including the inner corpse receiving casing B having the removable corpse carrier C and the outer protecting 60 casing D. F indicates the table or other support for the casket, and G indicates the laying out board for receiving the corpse carrier C, prior to the insertion of the same 65 in the casing B.

The inner corpse receiving casing B includes a hollow cylindrical transparent body 10 formed of a suitable impervious material, such as glass or the like, and has associated therewith the end caps 11 and 12, which 70 are formed of the same material as the cylinder 10. Each of the end caps or closures 11 and 12 includes a disk shaped body 13 having the inwardly extending right angular annular flanges 14 which are 75 adapted to engage the outer surface of the terminals of the cylinder 10. When the corpse indicated by the numeral 15 is inserted in the cylinder 10, the end caps 11 and 12 are adapted to be secured tightly in 80 place, by a suitable cement or water glass as at 16, so as to render the inner casing B 85 air and water proof.

The corpse carrier C is adapted to be detachably associated with the inner casing B 90 and the same includes a rectangularly shaped pad or mattress 17, suitably braced so as to form a rigid structure to facilitate the insertion of the same into and out of the cylinder 10. The mattress 17 is preferably 95 curved transversely so as to conform to the configuration of the cylinder. The outer or head end of the mattress 17 has eyes 18 or the like secured thereto, which are adapted to detachably receive hooks or snap fasten- 100

ers 19 carried by the inner terminals of the pulley straps 20, which are used to insert the mattress into the case B as will be hereinafter more fully described.

5 The outer casing D is preferably constructed of wood or the like suitably carved or ornamented, so as to present a pleasing appearance to the eye, and includes a rectangular box like structure having the side walls 21, the lower wall 22, the top wall 23 and the end walls 24. The top or cover 23 is preferably curved so as to present a substantially semi-cylindrical construction, so as to conform to the configuration of the 10 inner cylindrical casing B. The lower rear edge of the cover 23 is pivotally secured to the upper edge of one side wall 21 by suitable hinges 25, and the forward portion of the cover 23 and the other side wall 21 15 carries suitable companion sections, of a fastener 26. While as shown, the cover or top wall 23 is formed of one part and hingedly secured to the side wall 21, it is to be understood that the same may be made 20 in two parts and slidably associated with the main portion of the casing B. In this case, the lower half of the cover should be put on from the foot and making a half couch effect, then the top end should be 25 slipped on making the case complete. The interior of the outer casing D has associated therewith at equi-distantly spaced points, supporting cleats 27, which have their upper surfaces arcuately curved so as to receive and support the inner casing B. The 30 end walls are secured to the lower wall 22 by suitable hinges 28 at their lower ends, and the same are adapted to swing outwardly and downwardly to a plane below the body 35 of the outer casing B, when the casket is in position for receiving the corpse 15. When the end walls 24 are in their closed 40 positions, the same are locked by suitable detachable fastening means 29.

45 The rear end of the cylinder 10 has associated therewith a suitable air extracting means 30 so that when the end walls 11 and 12 are placed and sealed into position, the air can be exhausted from the interior of the 50 said body. The end wall 12 is provided with an inwardly extending slot 31 so as to receive the air exhausting means 30 when the same is placed in position on the cylinder.

55 In operation of the improved casket, the cover 23 is swung open, and the end walls unlocked and swung downwardly, and the cylinder 10 is placed in position in the outer casing D with the end walls 11 and 12 removed. The casket is then placed on the 60 table or other support F directly in front of the laying out board G, which might be of the ordinary or any preferred construction. As shown the table F is lower than the laying out board G. The carrier C is

then placed on the laying out board G and 65 the corpse placed in position thereon. The pulling straps 20 are then inserted through the cylinder 10 and the fasteners 19 are hooked through the eyes 18. The body can then be easily placed into the cylinder 10 70 by pulling on the straps 20 and after the corpse 15 and the carrier 17 is in position in the cylinder, the straps 20 are removed from the carrier. The end caps 11 and 12 are then inserted on the cylinder 10 and 75 sealed into position after which the air is extracted from the cylinder, and the end walls 24 and top wall 23 swung into position and locked.

80 From the foregoing description it can be seen that an improved casket is provided of simple and durable construction which will permit of the easy insertion of the corpse into the casket and preserves the corpse against perceptible deterioration for a considerable length of time.

Changes in details may be made without departing from the spirit or scope of my invention; but,

90 I claim:

1. A burial case for permitting the viewing of the corpse and for protecting the corpse comprising an outer ornamental protecting casing, transversely extending supporting cleats arranged in the casing, an 95 inner transparent corpse receiving case arranged in the protecting case and disposed upon said cleats, movable end caps for the inner transparent corpse receiving case, the outer protecting case including a removable 100 cover for exposing to view the inner transparent corpse receiving case, and hinged end walls for the outer protecting case arranged in direct alinement with the removable end caps of the inner transparent corpse 105 receiving case, as and for the purpose specified.

2. A burial casket for permitting the viewing of the corpse and for protecting the corpse comprising an outer protecting 110 opaque or ornamental case, transversely extending cleats arranged in the case, a cylindrical transparent corpse receiving case arranged in the outer protecting case, and resting upon said cleats, removable end caps 115 for the corpse receiving case, the corpse receiving case being removably associated with the outer protecting case, means for hermetically sealing the end caps in position against removal, means for permitting the withdrawal of air from the corpse receiving case, a swinging cover for the outer opaque protecting case for permitting the exposing of the corpse receiving case, hinged 120 end walls carried by the protecting case arranged in alinement with the removable end cap adapted to be thrown downward in a 125 plane below the same, and fasteners carried

by the side walls of the outer protecting case for engaging the end walls to hold the same against accidental displacement.

3. In a burial casket for permitting the viewing of the corpse and for protecting the corpse, a transparent case including an elongated cylindrical body having both of its opposite ends open, removable end caps for

the open ends including disk bodies and inwardly extending right angularly disposed 10 annular body engaging flanges, means hermetically sealing said flanges to the body, and means for exhausting the air from said transparent body.

THOMAS BRADLEY.
